Dorsey L. Helm, 9732 Dayton Ave. N.,
Seattle, Wash. 98103

Filed Apr. 4, 1974, Ser. No. 457,992

Term of patent 14 years

Int. Cl. D8—05

U.S. Cl. D8—51

FIG. 1 is an isometric view of a hand held pick-up implement, showing my new design;

FIG. 2 is a bottom plan view thereof;

FIG. 3 is an end view taken from the grip end thereof;

FIG. 4 is an isometric view showing a second embodiment of my new design;

FIG. 5 is a bottom plan view thereof; and

FIG. 6 is an end view taken from the grip end thereof.

The right sides of the two embodiments, not shown in the drawings, are substantially the same as the respective sides shown therein.

I claim:

The ornamental design for a hand held pick-up implement, substantially as shown and described.
